US0D1066354S

(12) **United States Design Patent** (10) Patent No.: **US D1,066,354 S**
(45) Date of Patent: ** Mar. 11, 2025

(54) **DISPLAY SCREEN WITH GRAPHICAL USER INTERFACE**

(71) Applicant: **Liberty Mutual Insurance Company**,
Boston, MA (US)

(72) Inventors: **Richard Brigham Pendleton**, Eliot,
ME (US); **Troy Michael Campano**,
Dover, NH (US); **Christopher Weed**,
Oregon, WI (US)

(73) Assignee: **LIBERTY MUTUAL INSURANCE
COMPANY**, Boston, MA (US)

(**) Term: **15 Years**

(21) Appl. No.: **29/770,494**

(22) Filed: **Feb. 12, 2021**

Related U.S. Application Data

(63) Continuation of application No. 29/750,635, filed on
Sep. 15, 2020, now Pat. No. Des. 990,483, and a
continuation of application No. 29/750,630, filed on
Sep. 15, 2020, now Pat. No. Des. 990,482.

(57) **CLAIM**

The ornamental design for a display screen with graphical user interface as shown and described.

DESCRIPTION

The FIGURE is a view of a display screen with graphical user interface showing the new design. The outermost broken line perimeter illustrates a display, screen, or the like or portion thereof and forms no part of the claimed design. All other broken lines depict features of a display screen with graphical user interface that form no part of the claimed design.
